UNITED STATES PATENT OFFICE.

WALTER B. MARBLE, OF CHICAGO, ILLINOIS.

VANITY CASE.

Application filed December 14, 1922. Serial No. 606,844.

To all whom it may concern:

Be it known that I, WALTER B. MARBLE, a citizen of the United States, and a resident of Chicago, county of Cook, and State of Illinois, have invented certain new and useful Improvements in Vanity Cases, of which the following is a specification.

This invention relates to vanity cases.

One of the objects of the invention is to provide a compact article of the character described and a device so constructed and arranged that toilet accessories such as rouge and powder compacts contained therein will be readily accessible.

Another object of the invention is to provide an article of the character described that is simple in construction, comprises few parts, is neat in appearance and can be economically manufactured.

Further objects of the invention will appear from the following description taken in connection with the drawings which form a part of this application and in which,

Fig. 1 is an elevational view of a device of the class described showing the vanity case in open position.

Fig. 2 is an enlarged sectional view of the construction shown in Fig. 1, the case being closed.

Fig. 3 is a transverse sectional elevation showing in top plan the vanity case with the cover removed and

Fig. 4 is an elevational view partly broken away showing the swiveled member on which the toilet accessories or compacts are mounted.

The invention briefly described comprises a vanity case consisting of a pair of hinged members such as a base member and a cover and a member mounted intermediate the base and cover and having means for securing thereto a plurality of toilet accessories. The cover has secured thereto a mirror and the intermediate member is swiveled to the vanity case and has secured thereto a pair of compacts such as a rouge compact and a powder compact arranged back to back or facing outwardly. Either of these compacts may be used at will by turning the intermediate member on the swivel. In this way the user of the case can utilize one mirror when applying the rouge or the powder. Further details of the invention will appear from the following description.

The vanity case illustrated comprises a base 10 and the cover 11, these parts being

hinged together by complementary hinge members 12 and 13 connected by a pivot pin 14.

A mirror 15 is secured to the cover 11. 60

The toilet accessories, or in this instance, the rouge compact 16 and powder compact 17 are carried by a disc 18 having an annular flange 19 formed thereon. The flange 19 is swiveled on a pin 20 having a head 21 65 disposed within the flange and a ring 22 mounted on the pivot pin 14.

The central portion of the disc 18 is dished as shown at 23 and has a central opening 24 therein. 70

The rouge compact 16 is placed in the dished portion 23 of the disc 18 and thereafter the powder compact 17 is placed in the annular flange 19, the rouge compact and powder compact being arranged back 75 to back as shown in Fig. 2 and each of these compacts facing outwardly with reference to the disc 18.

The annular flange 19 has formed therein a groove 25 for receiving a split ring 26 80 and the ring 26 engages the outer peripheral portion of the powder compact and retains the powder compact and the rouge compact in position.

As shown in Fig. 3 the groove 25 does not 85 extend entirely around the annular flange 19 but is interrupted at 27 and 28 and therefore the ends of the split ring extend inwardly and may be engaged when it is desired to remove the ring. 90

The disc 17 at its dished portion 23 has formed thereon a pair of tabs 29 for the purpose of retaining a pad or puff 30.

A puff 31 for the powder compact is positioned in the annular flange 19. 95

As shown in Fig. 2 the material of the flange 19 is bent outwardly to form the groove 25 and this outwardly bent portion forms a shoulder 32 adapted to rest on an inwardly extending annular flange 33 formed on the base 10. 100

Any suitable form of catch may be provided for the casing 10, 11.

The device is used in the following manner. The case is first opened. The mirror 15 is then available and either of the compacts may be used. When it is desired to use the other compact the intermediate member is lifted and swung on its swivel pin 20 and again dropped to the position in 110 which the shoulder 32 will rest on the flange 33 of the base 10.

Although one specific embodiment of the invention has been particularly illustrated and described, it will be understood that the invention is capable of modification and 5 that changes in the construction and in the arrangement of the various cooperating parts may be made without departing from the spirit or scope of the invention as expressed in the following claims.

10. What I claim is:—

1. A vanity case comprising a casing consisting of a pair of members, and a member disposed intermediate said casing members and having toilet accessories secured to its 15 opposite faces.

2. A vanity case comprising a casing consisting of a pair of members, and a member disposed intermediate said casing members and reversible about one of its diameters and 20 having toilet accessories secured to its opposite faces.

3. A vanity case comprising a casing consisting of a pair of hinged members, and a member swiveled intermediate said casing members 25 and having toilet accessories secured to its opposite faces.

4. A vanity case comprising a casing consisting of a pair of members, and a member swiveled intermediate said casing members 30 and having toilet accessories secured to its opposite faces, one of the casing members having a mirror.

5. A vanity case comprising a casing consisting of a pair of hinged members, a member swiveled intermediate said members, a mirror secured to one of the casing members, and means for securing compacts to said intermediate member, arranged back to back.

40. A vanity case comprising a casing consisting of a pair of hinged members, a member swiveled intermediate said members to the hinged connection therebetween, a mirror secured to one of the casing members, and means for securing compacts to said intermediate member, arranged back to back.

45. A vanity case comprising a casing consisting of a pair of hinged members, a member swiveled intermediate said members to and pivoted on the hinged connection therebetween, a mirror secured to one of the casing members, and means for securing

compacts to said intermediate member, arranged back to back.

8. A vanity case comprising a casing consisting of a pair of hinged members, a member mounted intermediate said members, and reversible about one of its diameters a mirror secured to one of the casing members, and means for securing compacts to said intermediate member, arranged back to back. 55

9. A vanity case comprising a base member and a cover member hinged thereto, a member swiveled to said hinged connection, a mirror secured to the cover member and means for securing a pair of compacts to 60 said swiveled member, arranged back to back.

10. A vanity case comprising a base member and a cover member hinged thereto, a member swiveled to and pivoted on said 70 hinged connection, a mirror secured to the cover member and means for securing a pair of compacts to said swiveled member, arranged back to back.

11. A vanity case comprising a casing 75 consisting of a base and a cover for said base adapted to engage and close on said base and a member mounted in said casing, said member having an opening with a dished edge for receiving a compact and means for securing another compact to said member, arranged back to back with said first compact, said securing means and compact secured thereby coacting to secure said first compact in the dished opening. 80

12. In a vanity case, a swiveled member, and means for securing a pair of compacts to said member, facing in opposite directions.

13. In a vanity case, a swiveled member, 90 and single means for securing a pair of compacts to said member, facing in opposite directions.

14. A vanity case comprising a base, a cover hinged thereto, a disc pivoted to and 95 swiveled on the hinged connection between the base and cover, and a pair of compacts arranged back to back and secured to said disc.

In witness whereof, I have hereunto set 100 my hand this 2nd day of December, 1922.

WALTER B. MARBLE.
